STOCKING

Robert A. Folkman, Charlotte, N. C., assignor to
 Nebel Knitting Company, Charlotte, N. C., a
 corporation of North Carolina

Application June 7, 1937, Serial No. 146,883

1 Claim. (Cl. 66—182)

This invention relates to a full-fashioned stocking having a welt or doubled portion at the top thereof and having an upper leg portion extending below the bottom edge of the welt and having a main leg portion connected by knitting to the lower edge of the upper leg portion, said leg portion and upper leg portion and the welt portion being joined together, longitudinally of the stocking, by a seam in a conventional seaming machine.

5 In the present type of full-fashioned stockings there is a great demand for a stocking having a leg portion known as the chiffon or sheer type of hosiery and it has been found that at the junction point of the sheer leg portion with the upper leg portion where the seam crosses these portions, the breakage occurs. There are several theories as to the cause of this breakage but one of them is that the upper leg portion extending below the lower edge of the welt portion, is unable to withstand the stresses applied to the stocking on account of its being anchored at the welt portion to suitable supporters and on account of the flexing of the knee and the body movement of the legs of the wearer. In any event, there seems to be a great amount of lateral and longitudinal strains along the leg portions and breakage usually occurs at the junction point of the sheer leg portion with the upper leg portion on each side of the seam where it enters the upper leg portion.

10 This may be caused by the fact that the seamer loops do not penetrate each course of the sheer portion of the stocking and therefore some of these courses are not anchored as well as the others, resulting in breakage of these loops, and this breakage usually occurs in the extreme corner where the seam enters the upper leg portion of the stocking. Also, it is possible that the needle of the seamer in penetrating the fabric may cut or partially cut some of the threads thus weakening the same and causing rupturing of the threads at the junction point of the sheer portion with the upper leg portion on each side of the seam extending up the back of the leg.

15 In any event, it is an object of my invention to provide a re-enforced area extending along each side of the seam downwardly from the upper leg portion appearing immediately below the welt and extending substantially into the sheer portion of the stocking and preferably being of the inverted pyramid type so as to distribute the stresses and strains applied to this point of the stocking.

It is another object of this invention to provide a full-fashioned stocking having a sheer leg portion, an upper leg portion disposed adjacent the upper end of the main leg portion, and a welt

or doubled portion joined to the upper end of the upper leg portion, with the junction point of the upper leg portion and the sheer portion of the leg being further re-enforced on each side of the seam up the back of the leg, penetrating the sheer portion, the upper leg portion and the welt portion.

It is another object of this invention to provide a full-fashioned stocking having a welt portion, a top leg portion disposed immediately below the lower edge of the welt portion and a sheer main leg portion, with the upper leg portion being of single ply and knitted from substantially the same yarn as the welt is knitted with a plurality of courses in the lower edge of the upper leg portion not only having the welt yarn therein but also having the main leg yarn knitted along with the heavier welt yarn.

Some of the objects of the invention having been stated, other objects will appear as the description proceeds when taken in connection with the accompanying drawing, in which:—

Figure 1 is the rear perspective view of a stocking embodying the features of my invention;

Figure 2 is a front elevation of the upper end of a stocking with the front portion thereof broken away and showing my invention embodied therein;

Figure 3 is an enlarged schematic view of the right-hand portion of the re-enforced area forming the subject of my invention.

Referring more specifically to the drawing, the numerals 10 and 11 indicate the inner and outer layers of the welt of the stocking which are knitted together as at 12, and extending some distance below the junction point of the lower edges of the welt is a top leg portion 13, usually knitted from the same yarn as the two layers of the welt. These layers of the welt are usually made of a five thread yarn, and as is well known, when the welt has been knitted the lower edges thereof are interknitted. After interknitting the lower edges of the welt and five thread yarn is continued in the machine to knit a top leg portion or band around the stocking indicated as 13.

In order to provide the desired re-enforcement at the junction point of the sheer portion 17 with the top leg portion 13, just prior to the time when the knitting is changed to form the sheer leg portion which is usually to a two thread yarn, the leg yarn is interknitted with the welt yarn, beginning at dotted line 15, for as much as one course for each of the three carriers employed in the three carrier knitting machine. This gives three courses of seven thread yarn from the dotted

line 15 to the upper edge of the sheer leg portion 17, and then the five thread yarn is withdrawn from the needles except at the outer edges thereof where the welt yarn is fed to a gradually diminishing number of wales to form a triangular re-enforced area, which, when the stocking is seamed, provides the re-enforced seven thread area indicated at 14 in the drawing. This area 14 may extend further down into the leg portion than shown, or can extend less distance than that shown, the whole purpose being to distribute the stresses and strains which are localized in the corner where the seam 16 enters the top leg portion.

15 By forming this re-enforced area which becomes a triangular patch when the stocking is seamed together, it is seen that the internal stresses within the stocking are distributed around the weak point in the stocking and do not 20 converge to the point where the seam enters the top leg portion or band 13. On the other hand, these stresses are distributed evenly along the outer edges of the re-enforced area 14 and thus 25 breakage of the sheer leg portion of the stocking at and along the seam, is thus prevented.

By having one course of the main leg yarn for each carrier, or three courses of the three main leg yarns knit along with the welt yarn in the lower edge of the top leg portion, it is readily 30 seen that the sheer two thread yarns of the main leg portion are anchored in the more loosely knit top leg portion and thus the tendency for the leg yarn to pull out of the top leg portion at its point of introduction is eliminated, as 35 each main leg yarn has its end anchored in the loops of the lower courses of the top leg portion, and stresses and strains applied by the main leg portion at its juncture with the top leg portion are distributed evenly into the lower edge of the 40 top leg portion.

Throughout the specification, I have described the welt portion 13 and the top leg portion 17 as being of a five thread yarn, and the sheer leg portion as being of a two thread yarn. It is, 45 of course, understood that I am not limited to this type of yarn, as the welt yarn can have more than five threads in the yarn as well as less

than five threads therein, and likewise, the top leg portion can be knitted from any type of yarn desired and is not limited to the five thread yarn or to any particular yarn. It is also true that the sheer leg portion can be of a one thread yarn, a 5 one and one-half thread yarn, a three thread yarn, or any type of yarn ordinarily used in the making of a sheer main leg portion.

Although I have described the re-enforcing area 14 as being knitted from the welt yarn and 10 the two thread yarn of the sheer leg portion, another, and probably more practical way of forming this re-enforcing area 14, is to withdraw the welt yarn after the last courses have been knitted in the lower edge of the top leg portion embodying 15 also the sheer leg yarn, and forming the re-enforcing area with a splicing yarn, for example, a six thread yarn, along with the sheer leg yarn, thus making the area 14 contain the equivalent of an eight thread yarn. In fact, any desired 20 type of yarn, or any desired method of knitting can be employed in the formation of this area 14.

In the drawing and specification there has been set forth a preferred embodiment of the invention, and although specific terms are employed, 25 they are used in a generic and descriptive sense only, and not for purposes of limitation, the scope of the invention being set forth in the appended claim.

I claim:

A full-fashioned stocking having a seam extending longitudinally of the same and comprising a doubled or welt portion interknitted at its lower edge, a top leg portion interknitted with the lower edge of the welt portion and being 35 single ply and of substantially the same yarn as that from which the welt portion is knitted, a main leg portion of the sheer type interknitted with the lower edge of the top leg portion and having a plurality of courses of leg yarn knitted 40 in the lower courses of the top leg portion, and a re-enforcing area disposed on each side of the seam of the stocking and extending from the lower edge of the top leg portion into the sheer main leg portion, and interknitted with the top 45 leg portion and the main leg portion.

ROBERT A. FOLKMAN.
